UNITED STATES PATENT OFFICE.

RAY HORWITZ, OF CLEVELAND, OHIO.

MATERNITY-DRESS.

1,238,917.

Specification of Letters Patent. Patented Sept. 4, 1917.

Application filed June 4, 1917. Serial No. 172,608.

To all whom it may concern:

Be it known that I, RAY HORWITZ, a citizen of the United States, residing at Cleveland, in the county of Cuyahoga and State 5 of Ohio, have invented a certain new and useful Improvement in Maternity-Dresses, of which the following is a full, clear, and exact description.

The object of this invention is to provide 10 a maternity dress which may be of smart and beautiful appearance, and which will preserve its beauty and smartness as the waist portion thereof is progressively enlarged, as circumstances require.

15 The invention consists in the construction and combination of parts shown in the drawings and hereinafter described and pointed out definitely in the appended claims.

20 In the drawings, Figure 1 is a perspective view of a dress which embodies the invention when the sash thereof is tied in place to conceal the mechanical construction; Fig. 2 is a similar view when the sash is untied; 25 Fig. 3 is a perspective view of that part of the dress in which the invention is embodied. Fig. 4 is an elevation partly sectioned of the elastic waist band of the dress. Fig. 5 is a sectional plan of a portion of the elastic 30 waist band attached to the dress, and Fig. 6 is a horizontal sectional view at the waist line.

The dress consists of a waist 10, and a skirt 15 sewed thereto. Both the waist and 35 skirt, at their connected edges, are gathered, as shown. An elastic waist band 20 is secured over the connecting seam, by having its upper edge stitched to the waist and its lower edge to the skirt. This elastic 40 waist band is a cloth tube 21 containing one or more elastic bands 22.

Within the dress and extending across the waist band thereof is a girdle 30. This is made of pieces, preferably three pieces, of 45 inelastic webbing. The back piece 30^a is connected with the adjacent front pieces 30^b, 30^c, by lacing 25, whereby the length of the girdle may be enlarged as required. The two front members of the girdle are provided at their meeting edges in the middle of 50 the front of the dress by hooks and eyes, or other equivalent fastening devices.

The elastic waist band is stitched to the back portion of the girdle member 30^a, and 55 extends therefrom outside of the girdle in a stretched condition, and is then stitched to

the two front girdle members near their front meeting edges. Preferably also snap fasteners 24 are used to connect the elastic waist band to the two front girdle members 60 at points about midway between the ends of the said girdle members. It is evident, therefore, that the elastic waist band will contract the dress against the girdle between the above mentioned points of connection 65 with the girdle, however much the girdle may be extended by widening the laced gaps between the pieces thereof. In fact, externally, the dress will have, at the waist line, substantially the same gathered appearance 70 whether the girdle be large or small.

The waist opens in front, and at a point adjacent the meeting ends of the girdle members 30^b, 30^c. The skirt is also opened at the front, but a little to one side of the meeting 75 edges of said girdle members, said opening 16 extending downward for a suitable distance. A free flap portion 17 of the skirt projects beyond the end of the girdle to which it is attached, substantially as shown 80 in Fig. 3; and this free flap carries at its ends, attached to the inside of the elastic waist band, one of the members of a snap fastening device, the other of which will be fastened at a suitable point to the elastic 85 waist band which overlies the other front girdle member.

Having described my invention, I claim:—

1. In a maternity dress, the combination 90 of a waist and a skirt connected thereto, said skirt and waist being gathered at the waist line thereof, an elastic waist-band secured to and extending around the dress at the waist line, an extensible girdle within said dress at the waist line, which girdle is composed of a plurality of sections of which two sections meet at the front of the dress and are provided with fastening devices, and the other sections are connected together by extensible lacings,—said elastic waist 95 band being disconnected from the girdle at and adjacent the laced gaps between girdle sections, and being connected to said girdle sections at intermediate points, substantially as specified. 100

2. In a maternity dress, the combination 110 of a waist and a skirt connected thereto, said skirt and waist being gathered at the waist line thereof, an elastic waist-band secured to and extending around the dress at the waist line, an extensible girdle within said dress at the waist line, which girdle is com-

posed of a back section that is connected with the elastic waist-band near the middle of said girdle section and is disconnected from said waist band adjacent the ends of 5 said back girdle section, and two front sections which are connected respectively with the ends of the back girdle section by extensible lacing, the front ends of said front girdle section being provided with fastening devices, and the extensible waist band being connected with the front girdle sections adjacent the front ends thereof and being disconnected from said front girdle sections adjacent the rear ends thereof. 10
15 3. In a maternity dress, the combination of a waist and a skirt connected thereto, said skirt and waist being gathered at the waist line thereof, an elastic waist-band secured to and extending around the dress at the waist line, an extensible girdle within said dress at the waist line, which girdle is composed of a back section that is connected with the elastic waist-band near the middle 20

of said girdle section, and is disconnected from said waist band adjacent the ends of 25 said back girdle section, and two front sections which are connected respectively with the ends of the back girdle section by extensible lacings,—the front ends of said front girdle section being provided with 30 fastening devices, and the extensible waist band being connected with the front girdle sections adjacent the front ends thereof and being disconnected from said front girdle sections adjacent the rear ends thereof,—the 35 skirt of said dress with the extensible waist band attached thereto being extended as a free flap beyond the front end of one of the front girdle sections, said flap having a fastening device at its free end and the part of the waist band attached to the other front girdle section having a co-operating fastening device. 40

In testimony whereof, I hereunto affix my signature.

RAY HORWITZ.
